(57) CLAIM

The ornamental design for a hybrid connector assembly, as shown and described.

DESCRIPTION

FIG. 1 is a front and lower right perspective view of a hybrid connector assembly showing our new design. The broken lines in FIG. 1 are included for the purpose of illustrating portions of the hybrid assembly connector that forms no part of the claimed design;

FIG. 2 is a front elevation view of the hybrid connector assembly shown in FIG. 1. The broken lines in FIG. 2 are included for the purpose of illustrating portions of the hybrid assembly connector that forms no part of the claimed design; FIG. 3 is a rear elevation view of the hybrid connector assembly shown in FIG. 1. The broken lines in FIG. 3 are included for the purpose of illustrating portions of the hybrid assembly connector that forms no part of the claimed design; FIG. 4 is a left side elevation view of the hybrid connector assembly shown in FIG. 1;

FIG. 5 is a right side elevation view of the of the hybrid connector assembly shown in FIG. 1;

FIG. 6 is a top plan view of the hybrid connector assembly shown in FIG. 1. The broken lines in FIG. 6 are included for the purpose of illustrating portions of the hybrid assembly connector that forms no part of the claimed design; and, FIG. 7 is a bottom plan view of the hybrid connector assembly shown in FIG. 1.
